UNITED STATES PATENT OFFICE

ELVIS EDWARD DRAKE, OF NASHVILLE, TENNESSEE.

HEAD-BLOCK FOR HAY-PRESSES.

No. 813,409.

Specification of Letters Patent.

Patented Feb. 27, 1906.

Application filed October 6, 1905. Serial No. 281,626.

To all whom it may concern:

Be it known that I, ELVIS EDWARD DRAKE, a citizen of the United States, residing at Nashville, in the county of Davidson and State of Tennessee, have invented a new and useful Head-Block for Hay-Presses, of which the following is a specification.

The invention relates to improvements in head-blocks which are placed in baling-presses at intervals to separate the compressed hay into bales of suitable sizes.

Heretofore head-blocks have been provided with substantially V-shaped grooves to receive the wires for tying up the bales, but difficulty has been experienced in passing the wires through the grooves for arranging them around the bales while the baling-press is in operation, as the sharp or rough edges of the wire frequently embed themselves either in the wood of the head-block or in the bale, and it then becomes necessary to withdraw the wire and again attempt to pass it through the groove.

The object of the present invention is to obviate the above objection and to provide a head-block having grooves through which wires may be rapidly passed and in which the wires will be retained until the bales are tied.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is an elevation of a portion of a baling-press provided with head-blocks arranged at intervals. Fig. 2 is an enlarged sectional view of one of the head-blocks. Fig. 3 is a detail perspective view of the same. Fig. 4 is an enlarged detail view of a portion of the head-block and one of the grooves, illustrating the construction of the wire guiding and retaining means.

Like numerals of reference designate corresponding parts in all the figures of the drawings.

1 designates a head-block designed to be constructed in the usual manner of a plurality of layers of wood and adapted to be

placed in a baling-press 2 at intervals, as illustrated in Fig. 1 of the drawings, for separating the hay into bales of the desired size. The head-block is provided at each of its faces with wire-receiving grooves 3, having outwardly-converging side walls 4, forming tapering spaces for the wires and providing a constricted entrance. Within each of the grooves is arranged a metallic lining consisting of a rear wall 5 and outwardly-converging side walls 6, forming wire-engaging jaws and providing resilient expandable portions or sides which further constrict the longitudinal opening or mouth of the groove to a size less than the diameter of the wire. The rear and side walls 5 and 6 also present smooth unbroken surfaces for enabling a wire having either a smooth or rough end to be easily and quickly passed through the groove from one end to the other. The rear wall of the lining fits flat against the inner wall of the groove, and the expandable resilient sides engage the side walls of the groove at the inner portions thereof adjacent to the rear wall and firmly hold the lining in position in the groove, so that it is unnecessary to provide screws, nails, or other fastening devices for securing the lining to the head-block. This enables a perfectly smooth interior guiding-surface to be presented to the wires. The resilient side walls of the lining do not interfere with the removal of the wire when the proper force is applied, and in tying a bale the wire is readily drawn through the longitudinal mouths or openings of the grooves. As soon as the wire is placed under tension through the expansion of the bale it is quickly withdrawn from the grooves of the head-block, as will be readily understood.

Having thus fully described my invention, what I claim as new, and desire to secure by Letters Patent, is—

1. A head-block provided with a wire-receiving groove, and means located within the groove for guiding a wire through the same and for yieldably holding the wire in the groove.

2. A head-block provided with a wire-receiving groove, and means for yieldably retaining the wire in the groove.

3. A head-block provided with a wire-receiving groove, and a metallic lining having resilient sides spaced from the walls of the groove at the longitudinal mouth or opening thereof and constricting the same, said sides

being adapted to expand to permit the wire to be drawn through them.

4. A head-block having a wire-receiving groove provided with outwardly-converging side walls, and a metallic lining arranged within the groove and having converging side walls, said side walls being resilient to engage the inner portions of the side walls of the groove, and the outer portions of the 10 sides of the lining being spaced from the

walls of the groove and constricting the longitudinal opening or mouth of the same.

In testimony that I claim the foregoing as my own I have hereto affixed my signature in the presence of two witnesses.

ELVIS EDWARD DRAKE.
